DRAWER HANDLE

Ephraim Winer, Baltimore, Md., assignor to The National Plastic Products Company, Odenton, Md., a corporation of Maryland

Application January 8, 1954, Serial No. 28,417

Term of patent 14 years

(Cl. D10—8)

Fig. 1.

Fig. 2.

Fig. 3.

Fig. 4.

Fig. 5.

Fig. 1 is a view in perspective of a drawer handle showing my new design;

Fig. 2 is a front elevational view thereof with a portion shown partly broken away and in section;

Fig. 3 is a top plan view thereof with a portion shown partly broken away and in section;

Fig. 4 is a bottom view thereof; and

Fig. 5 is a sectional view of the drawer handle taken on the line 5—5 of Fig. 2.

I claim:

The ornamental design for a drawer handle, as shown.
